SHOWER BATH AND PAN

Allan Cheney, Cynwyd, Pa.

Application August 27, 1936, Serial No. 98,241

12 Claims. (Cl. 72—70)

The present invention relates to improvements in pans adapted to be embedded in the masonry floor of shower baths to provide a waterproof course therefor, and the invention aims generally to improve the construction of such pans as well as the construction of the shower bath floor.

Heretofore in the construction of a masonry floor for a shower bath stall, it has been customary to lay a sheet of lead on the masonry floor to prevent the seepage of water therethrough. It is very difficult to lay such a lead sheet free from depressions or pockets which collect water seeping through the floor, to the end that the lead sheet soon disintegrates from a chemical action between the lead and the concrete masonry. Furthermore, the lead sheet is so soft and pliable that it must be laid carefully and then protected against deformation during the laying of the masonry floor, and great difficulty has been experienced due to workmen walking on the sheet before the masonry floor is laid. Furthermore the mortar of the masonry floor does not in any way adhere to lead sheet and when it expands and contracts due to sudden changes from hot to cold water, cracking and loosening of the floor often results.

My invention aims to overcome the above and other disadvantages by providing a pan fabricated from a metal, such as copper, which will not rust or corrode, which will be mechanically keyed to the masonry floor and provide an impervious waterproof course for draining any seepage to the floor drain.

My invention will be better understood by reference to the accompanying drawing illustrative of one preferred construction embodying the invention and in which

Fig. 1 is a central sectional view of a floor of a shower bath stall with my improved shower pan installed therein;

Fig. 2 is a fragmental perspective view of my improved shower pan; and

Fig. 3 is an enlarged detail sectional view through the pan on the line 3—3 in Fig. 2.

In the illustrated embodiment of the invention, the shower bath may be constructed upon a masonry foundation 10, over which is laid a course of building blocks 11, as for example terra cotta blocks, commonly used by the building trades. The size of the stall may be defined by vertical walls 12, inside of which is the usual wainscot 13, which may be of marble, glass, tile or other suitable material. A floor drain 14 may be embedded in the block course 11 at any convenient place.

A shower pan 15, which advantageously is of sheet copper, is of any desired shape to conform to the shape of the stall and is provided with upstanding side flanges 16 and end flanges 16a. The pan is laid over the course of blocks 11 and is embedded in a layer of mortar 17 above and below the pan. The upstanding flanges 16 and 16a of the pan extend upwardly between the walls 12 and wainscot 13 so that there will be no chance of leakage at the edges of the pan, and these flanges 16 may be bonded to the walls by a layer of mortar (not shown). The usual tile or other suitable finish 18 may be provided for the upper surface of mortar layer, or the upper surface of the mortar layer 17 may be trowelled smooth as desired.

The pan 15 is advantageously formed with a plurality of stiffening ribs 19 in its surface to reinforce and stiffen the body of the pan and preferably the sides of these ribs are inclined or undercut as at 20 so as to securely bond with the mortar 17. As herein illustrated the ribs 19 are shown as dovetail ribs extending transversely of the pan body, but it is to be understood that they may be of other cross-section and may be otherwise arranged in the body of the pan.

The body of the pan 15 between the ribs 19 constitutes water drainage grooves or channels 21 and preferably these channels extend from the marginal side flanges 16 inwardly toward the center of the pan 15 so as to drain any water that may seep through the course 17 centrally of the pan and toward the drain 14. In the embodiment of the invention illustrated wherein the ribs 19 are disposed transversely of the pan 15, the said ribs may be flattened centrally of the pan to provide a relatively wide drainage channel 22 communicating with all of the grooves 21.

When installing the pan, the workman has merely to cut an opening as at 23 in the body of the pan to receive the drain 14 and to secure the pan around said opening tightly to the drain 14 as by clamping. A thin layer of mortar having previously been spread over the course 11 of blocks, the pan is ready to be pressed into place. When so pressed into place, the lower layer of mortar 17 fills the grooves formed on the under side of the ribs 19 and when the mortar hardens the pan is securely bonded to the course of blocks.

A layer of mortar 17 is then spread over the body of the pan and then fills the spaces 21 of the pan and completely embeds the body 15. When this layer of mortar hardens, the pan is adequately secured to the foundation as a whole.

by reason of the mechanical bond afforded by the ribs and grooves.

As is well known, all masonry construction is porous to some extent and permits the seepage 5 of water therethrough, and in the case of masonry employing the usual building mortar, the seepage is relatively rapid. Shower bath stalls constructed in accordance with my invention are adequately protected against seepage through 10 the room below by reason of the impervious non-corrodible pan which collects all seepage water and drains it to the drain 14 through small holes in the sides of said drain. Furthermore the construction of the pan which provides alternate 15 ribs or grooves, produces considerable flexibility between the sides of the ribs so as to accommodate expansion and contraction of the masonry covering mechanically bonded to the pan, due to sudden changes from hot to cold water, without 20 liability of cracking or loosening of the masonry covering.

It is advantageous that the upstanding flanges 16 and 16a of the pan be ribbed so that they may be mechanically bonded to the walls 12 or 25 wainscot 13 or both. In the illustrated form of the invention, wherein the ribs 19 extend transversely of the body of the pan, the side flanges 16 may be integral with the body of the pan, but the end flanges advantageously are formed of 30 separate ribbed sheets secured to the end edges of the pan bottom and side flanges 16, as by soldering. Advantageously, the ribs adjacent the lower edges of the end flanges 16a are flattened as at 24 so that they may be soldered to a 35 plain edge portion 25 of the pan bottom. Preferably the ends of the end flanges 16a extend around the corner adjacent the ends of the side flanges and are secured thereto, so as to reinforce and strengthen the corners of the pan.

40 It will be apparent to those skilled in the art that the invention is not restricted to the particular shape or arrangement of the ribs or other details of the specific construction shown which is intended only as illustrative of the invention.

45 I claim:

1. A shower bath stall floor, a foundation, a course of masonry above the foundation, and an impervious metal shower pan embedded in and mechanically keyed to said masonry course, a drain outlet within the marginal edges of the 50 pan and means for draining water of infiltration from all areas of said pan to said drain outlet.

2. A shower bath stall comprising a foundation and vertical walls, a layer of cement over 55 said foundation, an impervious metal shower pan embedded in and mechanically bonded to said layer of cement and having peripheral integral upstanding flanges fitting said walls, and a wainscot fitted to the walls and in part overlying the flanges of said pan.

60 3. A shower pan adapted to be embedded in a cementitious floor of a shower bath stall having a floor drain, comprising an impervious sheet metal body conforming to the shape of the stall and fitting the floor drain, said pan being formed 65 with a plurality of alternate ribs and grooves for mechanical bonding engagement with the cementitious floor above and below it, and means for draining the water of infiltration from said grooves to the floor drain.

70 4. A shower pan adapted to be embedded in a cementitious floor of a shower bath stall having a floor drain comprising an impervious sheet metal body conforming to the shape of the stall and fitting the floor drain, the body of said pan 75

being formed with a series of alternate transverse ribs and grooves adapted to be embedded in the mortar, said grooves being intercommunicating in the region of the center of the pan to permit water of infiltration collected by said 5 grooves to be drained to the floor drain.

5. A shower pan adapted to be embedded in a cementitious floor of a shower bath stall having a floor drain comprising an impervious sheet metal body conforming to the shape of the stall 10 and fitting the floor drain, the body of said pan being formed with a series of alternate transverse ribs and grooves adapted to be embedded in the mortar, said ribs being flattened along at least one section of the pan to provide a 15 drainage valley communicating with all of said grooves whereby water of infiltration collected in said grooves may be drained to the floor drain.

6. A shower pan adapted to be embedded in a cementitious floor of a shower bath stall which is provided with a floor drain, comprising a sheet metal pan conforming in shape to the stall and formed with peripheral upstanding flanges, the body of said sheet being formed with transversely arranged alternate dovetail ribs and 20 grooves adapted to be bonded to said cementitious floor, and means establishing drainage communication from all of said grooves to the 25 floor drain.

7. A shower pan adapted to be embedded in a cementitious floor of a shower bath stall which is provided with a floor drain, comprising a sheet metal pan conforming in shape to the stall and formed with peripheral upstanding flanges, the body of said sheet and flanges being formed with 30 transversely arranged alternate dovetail ribs and 35 grooves adapted to be bonded to said cementitious floor, and means establishing drainage communication from all said grooves to the floor drain.

40 8. A shower pan for shower bath stalls comprising an impervious sheet metal body of substantial area and provided with a drainage outlet within the marginal edges thereof, said body being provided on the upper surface with means 45 for mechanically bonding the sheet to a layer of cementitious material, and for draining water from all portions of its area toward said drainage outlet.

9. A shower pan for shower bath stalls comprising an impervious sheet metal body of substantial area provided with a drainage outlet within the marginal edges thereof, said body being provided on the upper surface with expandable means for mechanically bonding the sheet 50 to a layer of cementitious material whereby the bonding means of the metal pan body may expand and contract to accommodate expansion and contraction of the cementitious layer, said expandable bonding means being so constructed and 55 arranged as to permit drainage of water from all portions of said pan toward said drainage outlet.

10. A shower pan for shower bath stalls comprising an impervious sheet metal body of substantial area provided with a drainage outlet 60 within the marginal edges thereof, said body being deformed to provide means adapted to effect a mechanical bond with a layer of cementitious material and to permit drainage of water from all portions of its area toward said drainage 65 outlet.

11. A shower pan for shower bath stalls comprising an impervious sheet metal body of substantial area provided with a drainage outlet within the marginal edges thereof, said body be- 70

ing deformed to provide means adapted to effect a mechanical bond with a layer of cementitious material on opposite sides thereof and to permit draining of water from all portions of its area toward said drainage outlet.

5 12. A shower pan for shower bath stalls comprising an impervious sheet metal pan formed with a bottom and upstanding side walls, said

bottom being of substantial area and provided with a drainage outlet within the marginal edges thereof, said bottom and side walls being provided with means for mechanically bonding the pan to layers of cementitious material and to 5 permit draining of water from all portions of its area toward said drainage outlet.

ALLAN CHENEY.
